UNITED STATES PATENT OFFICE.

EDITH E. LEVETT, OF NEW YORK, N. Y.

DESIGN FOR A TOY ANIMAL.

Application filed June 14, 1923. Serial No. 6,497. Term of patent 14 years.

To all whom it may concern:

Be it known that I, EDITH E. LEVETT, a citizen of the United States, and a resident of the city of New York, borough of Manhattan, in the county and State of New York, have invented a new, original, and ornamental Design for a Toy Animal, of which the following is a specification, reference being had to the accompanying drawing, forming part thereof.

The figure is a front view of the embodiment of my design in a toy animal, and the design comprises essentially a conventionalized animal standing, the arms arranged in position to hold a musical instrument, the anatomical features and characteristics being represented by musical symbols.

I claim:

The ornamental design for a toy animal, as shown and described.

EDITH E. LEVETT.
